BEER BARREL

Daniel J. Reed, Milwaukee, Wis., assignor to A. O.
Smith Corporation, Milwaukee, Wis., a corpo-
ration of New York

Application March 24, 1934, Serial No. 717,128

6 Claims. (Cl. 220—66)

This invention relates to a metal beer barrel. The principal object of the invention is to provide means for absorbing blows and sudden shocks delivered longitudinally of the barrel on the end edge, thereby preventing injury to the body of the barrel and to the lining material therein.

Other objects will appear hereinafter.

The accompanying drawing illustrates various embodiments of the invention.

Figure 1 is a detail section through one corner of a barrel showing one embodiment of the invention.

Fig. 2 is a similar view showing another embodiment.

Fig. 3 is a similar view showing still another embodiment.

Fig. 4 is a similar view illustrating a modification applicable to all embodiments.

The embodiment shown in Figure 1 consists principally of the cylindrical body 1 of the barrel, the end head 2 and the chime 3. The several parts are preferably formed of sheet metal, the body 1 being rolled from a single flat sheet and welded on a longitudinal line by electric flash welding, the head 2 being pressed from a flat sheet to provide a dished, central portion and a circumferential cylindrical skirt 4 adapted to fit snugly within the end of the body 1 and to be welded thereto at a circumferential line 5 adjacent the inner corner of the head by continuous electric resistance welding, and the chime 3 being formed of a single sheet of metal in a manner more fully set forth in copending application Serial Number 684,497, filed August 10, 1933, by William R. Kepler, for Chimes for barrels and method of making them, and assigned to a common assignee herewith.

The chime 3 may be of any suitable construction, that illustrated being found to be very satisfactory. It consists of a flat end ring 6 having its inner edge bent upwardly and over forming a bead 7 and providing a flat reinforcing section 8 for the ring 6, and having its outer edge curved into a bead 9 and extending upwardly like a sleeve 10 along the body 1 of the barrel. The end edges of the body 1 and head skirt 4 engage the section 8 at about the center line of the ring 6, and the sleeve 10 is key welded or otherwise secured to the end of the barrel as at 11.

In carrying out the invention, the skirt 4 of the head 2 is provided with one or more circumferential corrugations or ribs 12 between the chime 3 and the line of welds 5 and 11. This

bead or rib 12 functions to provide resilience to absorb the energy of the most severe shocks, and to protect the main container portion of the barrel from injury. The corrugations or ribs 12 may extend for the full circumference of the barrel or may be interrupted at intervals depending upon the stiffness desired. 5

In the embodiment of Figure 1, the body 1 of the barrel is not beaded, and its end portion tends to absorb the shock by permanent deformation while the bead 12 in the skirt 4 of the head and the bead 9 in the chime tend to absorb the shock by permanent and elastic deformation. Where the shock is unusually great, it is found that the body 1 tends to form a bead similar to 15 bead 12 and at the same location, thus absorbing excess shock by permanent deformation of the metal. Cushioning the shock in this manner gives a greater time for absorbing the energy of the shock and tends to prevent undesired injuries to the barrel. 20

In the embodiment shown in Fig. 2, the body 1 also has a circumferential corrugation, rib or bead 13 corresponding to bead 12 in the skirt 4 of the end head and complementary thereto. 25 This embodiment gives a greater cushion effect and absorbs more of the shock at the beads 12 and 13.

In the embodiment illustrated in Fig. 3, the body 1 does not extend fully to the section 8 of 30 the chime 3, but only the skirt 4 of the head engages the chime at the end of the skirt. The skirt is corrugated or beaded circumferentially at 12 similar to the other embodiments, but the body 1 is not beaded. In this embodiment, a 35 greater cushioning effect is obtained and shocks are absorbed by the beads 12 and 9.

The selection of the embodiment to be used and of other embodiments will depend largely upon the size and weight of the barrel and the 40 general type of handling it will receive.

The modification illustrated in Fig. 4 shows the application of the invention to a barrel of the type set forth in my copending application Serial Number 693,531, filed October 13, 1933. 45 In this case, the combination of features has been found to be particularly advantageous in preventing injury to the lining of the barrel at the juncture between the body 1 and head 2.

In making this modified form of Fig. 4, after 50 the head 2 is positioned properly in the body 1, a circumferential depression 14 is spun in the body 1 against the inner corner of the head 2. Then the two parts are welded together by a continuous electric resistance weld as close to 55

the inner corner of the head as possible. The structure thus provided tends to prevent deformation of the head adjacent the weld, and the rib 12 tends to absorb any excess shock which 5 might otherwise effect the undesirable deformation.

Various embodiments may be employed within the scope and spirit of the invention as set forth in the accompanying claims.

10 I claim:

1. A barrel comprising a container, a sheet metal circumferential skirt at the end of said container, and a sheet metal chime engaging the end of said skirt and having a portion welded 15 to the skirt near said container, said skirt and said chime each having one or more circumferentially extending beads for absorbing excessive endwise shock, said beads being located between said weld and the outer end of said chime.

20 2. A barrel comprising a sheet metal cylindrical body, an end head therefor having a sheet metal circumferential skirt fitting snugly in the end of said body, and a sheet metal chime having a flattened beaded ring seated against the end 25 of said skirt and a sleeve-like portion encircling and secured to the end portion of the cylindrical body by a weld at points remote from said flattened beaded ring, said skirt having a bead extending circumferentially thereof, and said sleeve 30 of said chime having a circumferential bead, both of said beads being adapted to absorb shock and being located between said weld and the outer end of said chime.

35 3. A barrel comprising a sheet metal cylindrical body, an end head therefor having a sheet metal circumferential skirt fitting snugly in the end of said body, and a sheet metal chime having a flattened beaded ring seated against the end of said skirt and the end of said cylindrical 40 body and a sleeve-like portion encircling and secured to the end portion of the cylindrical body by a weld at points remote from said flattened beaded ring, said skirt having a bead extending circumferentially thereof, and said sleeve of

said chime having a circumferential bead, both of said beads being adapted to absorb shock and being located between said weld and the outer end of said chime.

4. A barrel comprising a sheet metal cylindrical body, an end head therefor having a sheet metal circumferential skirt fitting snugly in the end of said body, and a sheet metal chime having a flattened beaded ring seated against the end of said skirt and the end of said cylindrical 10 body and a sleeve-like portion encircling and secured to the end portion of the cylindrical body by a weld at points remote from said flattened beaded ring, said skirt and said body portion 15 having a bead extending circumferentially thereof and said sleeve of said chime having a circumferential bead, both of said beads being adapted to absorb shock and being located between said weld and the outer end of said chime.

5. A barrel comprising a sheet metal cylindrical body, an end head therefor having a sheet metal circumferential skirt fitting snugly in the end of said body, and a chime engaging the end of said skirt for transmitting shocks thereto, said skirt having a corrugation or bead extending 25 circumferentially thereof to allow absorption of shocks by deformation of the metal of the skirt and said cylindrical body having a shoulder spun therein adjacent the inner corner of the head and being welded to said head at said shoulder. 30

6. A barrel comprising a sheet metal cylindrical body, an end head therefor having a sheet metal circumferential skirt fitting snugly in the end of said body and extending beyond the end 35 of said body, and a sheet metal chime having a flattened beaded ring seated against the end of said skirt and a sleeve-like portion encircling and secured to the end portion of the cylindrical body, said skirt having a bead extending circumferentially thereof and said sleeve of said chime 40 having a circumferential bead, both of said beads being adapted to absorb shock.

DANIEL J. REED.
